British and International Patent Applications filed in Great Britain January 2, 1948, and in the United States Patent Office April 28, 1953, Serial No. 57,450.

UNITED STATES PATENT OFFICE

2,636,644

COLLAPSIBLE TUBULAR CONTAINER

Albert Taylor, London, England, assignor to Burroughs Wellcome & Co. (U. S. A.) Inc., Tuckahoe, N. Y., a corporation of New York

Application October 30, 1948, Serial No. 57,450

In Great Britain January 2, 1948

2 Claims. (Cl. 222—92)

1

This invention relates to improvements in or relating to collapsible tubular containers and has particular reference to containers filled with medicaments or other relatively valuable contents.

As is well known in the case, for example, of the ordinary tooth paste tube, it is a matter of some difficulty to eject the last portion of the contents of the tube. The waste involved through the tube being thrown away whilst still containing a fraction of its original contents is not serious in the case of such a commodity as tooth paste, but it is appreciable when a relatively valuable material forms the contents of the tubular container. For example, in the case of oil-wax suspensions of penicillin containing 25,000 international units of penicillin in each millilitre of the suspension, it is found in practice that in order to be certain that at least the stated quantity of 20,000 units of penicillin may be available for use when the tubular container is squeezed it is necessary to pack approximately 30,000 units of penicillin in the tubular container as about 8,000 units is left behind in the shoulders and nozzle of the tubular container when the tubular container is squeezed out in the normal fashion.

It is the object of this invention to prevent this wastage of valuable medicaments or other valuable contents of collapsible tubular containers.

In accordance with our invention we first partially fill an inverted tubular container with the desired medicament or other main contents in fluid, semi-solid or paste form, and then place on top thereof in the inverted tubular container a small quantity of an inert semi-solid material which is cheaper or more readily available than the main contents of the container and immiscible or not readily miscible therewith at normal storage temperature and which has no injurious effect either upon the main contents of the tubular container or upon the body or any material to which such main contents are to be applied. The open end of the tubular container is then closed and sealed in the usual manner.

The invention includes the method of filling a collapsible tubular container and also the filled containers.

When the tubular container is squeezed the inert semi-solid material functions, in effect, as a piston, and the desired contents are fully expelled, whereafter a little of the inert semi-solid material is expelled. Thus, the full amount of the valuable contents present is made available for use and the tubular container when it is thrown away contains only the inert material of relatively low value.

2

A layer of inert semi-solid material of $\frac{1}{4}$ inch in thickness is usually amply sufficient for the purpose of this invention. In the case of small tubes containing a millilitre or a little more of medicaments, less than half a millilitre of inert semi-solid material will be required, though excess will not do any harm.

The semi-solid material besides being inert and non-injurious as above specified, preferably has a specific gravity lower than the valuable contents of the tubular container and a melting point or softening point slightly above body temperature and above any temperature that the filled container is likely to experience during storage and use. It is fed into the tubular container in a molten state and floats upon the surface of the valuable contents of the tubular container in a sharply defined layer. Preferably it also has a higher viscosity than that of the valuable contents of the tubular container; it is then possible to know when all the valuable contents of the container have been expelled because there is a sudden increase in the force necessary to be applied to expel the contents by squeezing the tube when the higher viscosity material reaches the nozzle of the tube.

The semi-solid material serves a further purpose in preventing the movement of the fluid or semi-solid valuable contents within the tubular container.

The semi-solid material may be in the form of a jelly.

It may be distinctively coloured so that the user is aware that the whole of the desired contents of the tubular container have already been expelled and only the inert material remains.

As an example, and for purposes of illustration only, it may be stated that small tubular containers containing oil-wax suspensions of penicillin, 25,000 units of penicillin in each millilitre of a suspension thereof in a vehicle comprising 5.0% by weight of ceresin (British Pharmaceutical Codex) in arachis oil, the containers being fitted with long nozzles and being intended for intra-mammary injection of the penicillin suspension into the teat canals of cattle, may comprise as semi-solid material soft paraffin having a melting point of about 50° C. The suspension and the soft paraffin are delivered in turn to the open and inverted tubular containers, in accordance with customary manual or mechanical filling procedures. The soft paraffin is delivered at a temperature just above its melting point and immediately congeals. The tubular container is then sealed by welding and folding over of its open end.

The specific tubular containers just described are shown by way of example in the accompanying drawings, in which,

Figure 1 is a side elevation of the container, and

Figure 2 is a side sectional elevation of the container looking in a direction at right angles to the direction of sight in Figure 1.

The tubular container is indicated at 10 and has a long hollow nozzle 11 adapted for insertion into one of the teat canals of a cow. The screw-threaded removable cap is shown at 12. The container 10 is sealed by folding over of its end and crimping as shown at 13.

The penicillin suspension is indicated at 14 and the soft paraffin filling at 15.

What I claim is:

1. A tubular container having an outlet opening of restricted dimensions, a relatively larger collapsible body portion, a flowable plastic material containing a valuable antibiotic substance filling the collapsible body portion from the outlet opening to a point immediately adjacent the opposite end of the body portion, a relatively small amount of an inert flowable plastic material of low value, immiscible with the main

plastic contents, filling the extreme end of the body portion remote from the discharge opening, said inert plastic material having a melting point above body temperature, said plastic material being of a higher viscosity than the main plastic contents, so that it is possible to know when all of the plastic material containing the antibiotic is expelled due to the sudden increase in force required when the higher viscosity material reaches the outlet opening.

2. The tubular container of claim 1 in which the second plastic material mentioned is paraffin.

ALBERT TAYLOR.
